UNITED STATES PATENT OFFICE

1,970,017

GAS CANNON

Edward S. Peake, Westerville, Ohio, assignor to
The Kilgore Manufacturing Company, Wester-
ville, Ohio, a corporation of Ohio

Original application May 12, 1932, Serial No.
610,751. Divided and this application Novem-
ber 5, 1932, Serial No. 641,423

4 Claims. (Cl. 102—1)

This invention relates to improvements in gas cannons, and particularly to improvements in ammunition adapted to be used in such cannons.

It has for its object to provide a gas-generating ammunition in measured form, soluble in liquid, consisting of pellets and the like, which may be coated if desired with some suitable material which moisture will not readily attack, but which may be quickly removed by the act of placing the 10 pellets in a generating chamber in contact with sufficient water to affect both coating and ammunition.

It is also an object of this invention to provide an ammunition consisting of carbide in stick form. 15 Such carbide may be coated with some suitable protective cover and separated into sections by means of indentations. The sections are broken along the indentations, which affords a surface along which water may attack the carbide for 20 producing gas in the generating chamber.

These and other advantages will appear from the following description taken in connection with the drawings, in which not only various forms of ammunition are shown but a form of gun 25 adapted to be used with each form of ammunition is shown.

This application is a division of my copending application, Ser. No. 610,751, filed May 12, 1932.

Referring to the drawings:

30 Figure 1 is a top plan view of one form of gun or mortar.

Figure 2 is a section on the line 2—2 of Figure 1.

Figure 3 is a section similar to Figure 2, showing a modified form of mortar and a modified 35 form of ammunition.

Figure 4 is a section through a further modified form of mortar, showing the form of ammunition used therewith.

Figure 5 is still another form of cannon showing 40 still another form of ammunition.

Figure 6 is a further form of cannon with the ammunition in stick form, separated into sections by means of indentations.

Figure 7 is a perspective view of a stick of 45 ammunition used in connection with the form shown in Figure 3.

Figure 8 is a perspective of a strip of ammunition used in connection with the mortar shown in Figure 4.

Figure 9 is a section on the line 9—9 of Figure 5.

In Figure 1 there is shown a top plan view of the mortar, which is supported on a base 1, which has upwardly extending side members 2 having bearings therein for supporting trunnions 3 of the 55 mortar 5. These trunnions are supported in the side members by means of screws 4 extending through the side members into the trunnions.

The lower end of the barrel of the mortar has a breech 6, which has extending through the 60 center thereof a hole 7 through which the gas

passes into the barrel for discharging a ball, such as the rubber ball 8 shown in the various figures of the drawings. Immediately below and to the back of the breech is a gas chamber 9, which is formed by an annular projection 10 of the walls 65 of the barrel, and a breechblock 11 fitting on the projection and retained thereon by means of a sleeve 12 threaded at 13 to the projection. This sleeve has an inwardly extending flange 12a which engages a shoulder on the breechblock. 70

Between the breechblock and the projection is a gasket 14, which serves to make the connection between the breechblock and the projection watertight. Located within the generating chamber 75 is water 15, which acts upon the carbide projected into the generating chamber for producing a gas for expelling the ball from the mortar. Leading into the generating chamber is an ammunition port 16 connected to a chamber 18 in a projection 19 for containing the pellets 17, such 80 as carbide in the form of balls suitably coated, or in the form of sticks, also suitably coated.

The upper end of the ammunition chamber 18 is closed by means of a door 20, while in the lower end adjacent the ammunition port is a valve 21, 85 which has in one side a pocket 22 to receive one of the ammunition pellets, and on rotation to discharge this pellet into the ammunition port for insertion into the generating chamber.

The part of the valve 21 adjacent the pocket 90 serves as a closure 23 for preventing the gas generated in the generating chamber escaping into the ammunition chamber. The valve is operated by means of a thumb piece 24 located on the upper end thereof, which has on one end a 95 finger 25 adapted to engage a stop 26. By means of the stop 26 the amount of rotation of the valve is limited so that it can rotate through about 180 degrees. In one position the pocket 22 will receive a pellet, while in the other position the 100 pellet will be discharged through the ammunition port with the closure 23 closing the passage-way from the port back to the ammunition chamber.

Suitably attached to some part of the breech-block is a hammer 27 pivoted at the point 28 to suitable ears formed on the breechblock. This hammer is adapted to engage a pin 29 supported by the breechblock and adapted to engage a cap 30 located immediately over a port 31 for igniting 105 the gas formed by the carbide within the generating chamber. The hammer is operated by means of a plunger 32 located in the chamber 34 and urged upwardly by means of a spring 33 located in the chamber. On the upper end of the 110 plunger is a roller 35, which engages a nose 36 located on the lower end of the hammer. The hammer is further actuated by means of a lan-

yard 37.

The ammunition used in connection with the 120

mortar shown in Figures 1 and 2 is in the shape of balls which are adapted to be inserted into the generating chamber for producing explosive gas. In the form shown in Figure 3 the ammunition is in the shape of a bar 38, which has therein grooves forming weak places 39 along which the bar may be broken into sections.

In the form of mortar shown in Figure 3 the upper end of the ammunition chamber is closed 10 by means of a screw plug 41. Between this screw plug and the upper end of the carbide bar is a spring 40, which urges the bar downwardly to be engaged by means of a plunger 42 which tends to break off one section of the bar and force it 15 into the generating chamber. This plunger is supported on its upper end by means of a pivot 43 on a lever 44, which is pivoted to some suitable part of the mortar at the point 45 intermediate its ends. The end of the lever remote from the 20 plunger is provided with a spring 46, which tends to force the plunger down against the bar of carbide for severing one of the sections therefrom and forcing the section into the generating chamber. There is provided in connection with the 25 ammunition chamber an end wall 47, which serves to stop the carbide bar as it is forced downwardly by the action of the spring 40. The mortar shown in Figure 3 is in all respects similar to the mortar shown in Figures 1 and 2 with the exception of 30 the manner in which the ammunition is fed and discharged into the combustion chamber.

In the form shown in Figure 4 a slightly modified form of ammunition chamber 48 is provided. This chamber is enlarged and is adapted to house 35 a strip of ammunition paper 49 carried on a transverse pin 50. This strip of ammunition has a plurality of pellets 51 arranged in spaced relationship from one end to the other of the strip, which is fed by means of a feeding wheel 52, which 40 has teeth 53 thereon to engage some suitable part of the strip for feeding the strip and the pellets carried thereby.

This wheel is supported on an axle 54 carried by the sides of the chamber 48. The wheel is rotated by means of an actuating arm 55 pivoted on the axle 54 of the feeding wheel 52. To this arm is pivoted one end of a plunger 56, as indicated by the numeral 57. The other end of this plunger has a cutting edge 58 adapted to engage the 50 strip of paper and sever a section therefrom containing one pellet. After this pellet has been severed from the other part of the strip it drops through the port 16 into the generating chamber.

In order that the feeding wheel may rotate 55 there is provided on the actuating arm an actuating spring 59, which is adapted to engage one of the teeth of the wheel each time that the plunger moves upward, and partially rotate the wheel to feed another pellet in position over the 60 port 16 so that another downward movement of the plunger will sever an additional pellet from the strip.

In order to prevent a backward movement of 65 the feeding wheel during the downward movement of the plunger a holding spring 60 is provided which engages a tooth to prevent backward rotation of the wheel. There is also provided, between the inner end of the actuating arm and a lug 62 located inside of the ammunition chamber, a spring 61 which tends to urge the inside 70 end of the arm upwardly and force the plunger downwardly.

In the form shown in Figure 5 the pellets 63 are in the form of cylindrical blocks located 75 within an ammunition chamber similar to that

shown in the other figures, and closed at its lower end by means of a stop wall 64. Extending upwardly from the lower end of the ammunition chamber and above the stop wall is a hollow projection 65, which has therein a plunger 66 which is urged downwardly by means of a spring 67 located between the upper wall of the hollow projection and a head 68 on the lower end of the plunger.

On the upper end of the plunger is a finger piece 69 which not only serves as a finger piece for elevating the plunger but also serves as a stop for limiting the downward movement of the plunger in injecting one of the pellets into the generating chamber. When the plunger is in its lower position the head 68 serves to close the passageway from the ammunition chamber into the generating chamber and thereby prevents the escape of gas from the generating chamber into the ammunition chamber.

In the form shown in Figure 6 the carbide ammunition is shown in the form of a stick 70, which has weakened places 71 therein along which the sections formed by the weakened places may be broken. The inlet port into the generating chamber is closed by means of a cover 72 pivoted at 73 and adapted to swing over or away from the port. As shown in Figure 6, the cover is removed from the port and the carbide stick 100 is inserted therein.

The sections are broken from the body of the carbide stick by means of a twist or bend in the stick, after which the stick as a whole is removed and the cover is placed over the inlet port so that no gas will escape from the generating 105 chamber.

Each piece of ammunition, such as the ball, cylindrical pellet, stick or strip is covered with some protecting material 74, such as wax paper, paraffin or some other suitable composition or 110 material. When the pellets or a section of the stick are discharged into the generating chamber a sufficient amount of this protective coating is removed so that the carbide of the ammunition may be acted upon by the water, and in addition to this the exposed surface of the coating 115 may be attacked by the water, though not readily.

I desire to comprehend within my invention such modifications as may be embraced within 125 my claims and the scope of my invention.

Having thus fully described my invention, what I claim as new and desire to secure by Letters Patent, is:

1. A new article of manufacture for use as 130 gas-forming ammunition in a gas cannon comprising spaced carbide balls, and a paper strip carrying said balls in predetermined relationship one to the other.

2. A new article of manufacture for use as 135 gas-forming ammunition in a gas cannon comprising a series of balls of carbide having weakened connections to one another and separable into sections.

3. A new article of manufacture for use as 140 gas-forming ammunition in a gas cannon comprising spaced carbide pellets, and a paper strip carrying said pellets in predetermined relationship one to the other.

4. A new article of manufacture for use as 145 gas-forming ammunition in a gas cannon comprising spaced carbide pellets, and an easily severed binder for holding the pellets in a predetermined spaced relationship to one another.

EDWARD S. PEEKE. 150
